BOX OR CARTON

Fred J. Ullrich, Kalamazoo, Mich., assignor of
one-half to Lee A. Fordon, Detroit, Mich.

Application July 31, 1939, Serial No. 287,568

2 Claims. (Cl. 229—39)

This invention relates to improvements in boxes or cartons.

The main objects of this invention are:

First, to provide a box or carton having automatic set-up provisions which are self locking in erected position of the box to effectively resist collapse or distortion.

Second, to provide a box or carton of the type described requiring a minimum of stock.

Third, to provide a folding box having improved automatic set-up and tuck-in closure provisions at the respective ends thereof adapting the box to be quickly and easily erected from flat knockdown position, filled, and then readily closed to provide a highly effective seal.

Further objects to relating details and economies of the invention will appear from the description to follow. The invention is defined in the claims. A structure embodying the features of the invention is illustrated in the accompanying drawing, wherein:

Fig. 1 is a perspective view of a preferred embodiment of the box according to my invention illustrating the same in erected and closed position and in particular showing the novel automatic set-up provisions on the bottom of the box in erected locked relation.

Fig. 2 is a view in section on line 2—2 of Fig. 1, illustrating the box bottom interiorly of the box, with the parts in erected position.

Fig. 3 is an enlarged fragmentary view in section on a line corresponding to line 3—3 of Figs. 1 and 2, further illustrating the aforesaid automatic set-up and tuck-in closure provisions.

Fig. 4 is a bottom plan exterior view illustrating the box of my invention in partially erected condition.

Fig. 5 is a top plan interior view somewhat similar to Fig. 4, being in section transversely of the box, illustrating the bottom set-up and locking provisions and the coaction of the side and end flaps during the process of erecting the box, the outline of the box in finally erected position being indicated in dotted lines.

Fig. 6 is an elevational view of the box in inoperative flat collapsed or knockdown form, being partially broken away to illustrate the relation of the bottom forming and automatic set-up elements in that position.

Fig. 7 is a view illustrating the blank employed in making the box of Figs. 1 to 6 and showing the formation and scoring thereof.

Fig. 8 is a view similar to Fig. 7, illustrating the blank of a slightly modified embodiment of the invention.

Fig. 9 is a perspective view illustrating a box formed from the blank of Fig. 7 with one end thereof open to illustrate the relation of the parts of the novel closure constituted by the blank of Fig. 7.

The present invention relates to collapsible or foldable boxes or cartons, being particularly directed to a box or carton which is quickly and easily set up or erected and securely held in erected position without necessitating several operations of manually tucking in, cementing, or lockingly engaging various elements provided for those purposes. Moreover, the invention relates particularly to a structure which is automatically self locking in set-up or erected form and to provide a structure which is amply rigid even when a relatively light grade of container stock is employed. In addition to possessing the foregoing characteristics, the structure of my invention is well adapted for manufacture by automatic machinery, being formed by a few simple scoring and transverse and longitudinal folding operations. It is likewise well adapted for the machine folding and securing or cementing of such few parts as are necessary for the production of the initially assembled knock-down form.

My invention likewise includes a box having a novel tuck-in type end closure designed to provide an effective and leak-proof closure and to be capable of being manipulated very quickly and easily to produce a seal which is practically airtight. If desired, the box in accordance with one aspect of the invention may be provided with closure of the type described at both the top and bottom thereof, whereby to provide a container which to all practical intents and purposes is airtight.

In the drawings, the reference numeral 1 indicates generally a box or container in accordance with the preferred embodiment of my invention, said box being provided with a bottom 2, formed by automatic set-up elements or parts to be hereinafter described, and having a top 3 which is generally indicated 3.

In Fig. 7 I illustrate a blank 4 of a suitable grade of carton or container stock from which the aforesaid box or carton may be made. This blank is scored as shown by dotted lines and is designated by the reference numeral 5 to outline the rectangular side panels 6, 7 and end panels 8, 9, the extreme side panel 7 being provided with a sealing flap 10 adapted to be adhesively secured to the opposite extreme end panel 8 by adhesive, indicated by the reference

numeral 81. The bottom forming, automatic set-up provisions of my invention are generally indicated by the reference numeral 11 and consist of end bottom flaps 12, 13 connected to end panels 8, 9 respectively, and side bottom flaps 14, 15 connected to side panels 6, 7 respectively, these last named side bottom flaps having wings 16, 17 connected thereto and defined by the scored fold lines 18.

The closure provisions of my invention are generally designated by the reference numeral 19 and will be hereinafter described in detail.

In the manipulation of the blank 4 to provide the initially assembled automatic set-up box, the flaps 12, 14, 13 and 15 are all bent inwardly on the transverse score line 5 connecting them to the respective panels 8, 6, 9, 7, being folded through 180 degrees on this line into parallelism and contact with said panels. The wings 16, 17 are then bent reversely of this fold onto the flaps 14, 15 respectively, the resultant positions of the various flaps and wings being indicated in Fig. 7 in broken lines. Panel 7 is then folded onto panels 9 and 6 along the score line separating the panels 7 and 9 and the end bottom flap 13 is secured to the reversely bent wing 17 by adhesive 171. The panel 8 is next folded onto panel 6 along the score line separating the same and the reversely bent wing 16 is secured to flap 12 by adhesive 161. To complete the folding and securing manipulations, the sealing flap 10, which overlaps end panel 8 in the position of the parts just described, is adhesively secured to that panel. No further operations are necessary so far as the formation and assembly of the automatic set-up provisions are concerned.

In order to render the aforesaid provisions self locking in operative erected position, the flaps 14 and 15 are conformed to provide the coacting notched open tongues 20, 21 respectively, which in the completely assembled knockdown condition of the container illustrated in Fig. 6 are disposed in opposing relation against the side walls of the box. The tongue 21 preferably has an inclined extremity 22 to guide the other tongue 20 into locking position during the act of setting up the box, as will be described.

With the parts in the foregoing flat condition, it is only necessary to set up the box to compress the extreme edges of the flat folded article, causing the sides and flaps attached thereto to move laterally relative to one another, as indicated by the arrows in Figs. 4 and 5, and at the same time spring the side bottom flaps 14, 15 downwardly toward horizontal position. Since the end flaps 12, 13 are adhesively secured to the side flaps, they are likewise drawn toward the final operative horizontal plane normal to the box walls. It should be noted that the wings 16, 17 are adhesively secured to the end flaps 12, 13 across the entire width and up to the common bottom corner of panels 6, 8 thereof, thus constituting in effect an integral, foldable, bottom corner bellows between flaps 12 and 14. The same is true of flaps 13 and 15 and the result is that the bottom of the box in erected condition is substantially continuous and leakproof at its corners.

In the foregoing movement, the locking tongues 20, 21 approach and pass one another, as illustrated in Fig. 5, tongue 20, riding on the inclined edge 22 of tongue 21, and when the box is erected to its final rectangular outline, these tongues snap into the locking engagement illustrated clearly in Fig. 2, the inclined edge or extremity 22

permitting the composite lateral and vertical movement of the opposed tongue 20 and leading it into the desired locking relation. The end bottom flaps 12, 13 lie on the thus interlocked side bottom flaps 14, 15 as illustrated in Fig. 2, to maintain the locked relation of the latter and complete the bottom or floor of the box. These end flaps 12, 13 have frictional side engagement with the side walls to further resist displacement of the parts.

In Fig. 8 there is illustrated a slightly modified embodiment of the foregoing structure wherein, instead of a pair of similar or notched open locking tongues, I employ a tongue 23 on the side bottom flap 15 and a locking slit 24 on the side bottom flap 14, these two elements coacting in practically the same manner as the tongues 20, 21 of the first described embodiment. I find that in the setting up operation the tongue 23 exerts sufficient pressure on side flap 14 to cause the tongue to enter the slit 24 and effect locking engagement with the curved end thereof.

In the embodiments of both Figs. 7 and 8, it is desirable that the cementing or securing flap 10 lie interiorly of the box and for this purpose I cut away the end bottom flap 12 at 25 to accommodate the sealing flap 10 when the flap 12 is folded to the position indicated in broken lines and the blank is finally assembled in flat condition.

The box of my invention includes a novel tuck-in sealing or closure arrangement 19 for the top thereof. As illustrated in Fig. 7 this arrangement consists of a tuck-in sealing member 26 connected to the side panel 7 and a further relatively continuous or uninterrupted member 27 for the end and side panels 6, 8, 9, which is separated from the tuck-in member 26 by a notch 28. The member 26 is scored at 29 to provide a bendable tongue 291 enabling the ready manipulation thereof in the tucking operation to be described, while the member 27 is preferably perforated at 292 and scored at 293 to provide top end flaps 30 adjacent the walls 8, 9 and a readily foldable gusset 31 connecting these flaps with a top side flap 32 adjacent to and connected to wall 6. This gusset is further perforated or slotted at 33 whereby when the end flaps 30 are folded inwardly toward one another, as illustrated in Fig. 7, the gusset first bends along perforated lines 292 and 33 to form a tuck-in chute 34 in the member 27 between flap 31 and the body of the gusset. This chute affords a relatively large-mouth opening to receive the lead-in end or tongue 291 of the tuck-in flap 26.

In Fig. 8 I illustrate an embodiment of the tuck-in top which is similar to that of Fig. 7, with the further feature that the top flaps are gusset-connected all the way around the top. An extra gusset 36 replaces the notch 28 of Fig. 7, and connects the tuck-in flap 26 to end flap 30. Furthermore, the arrangement of Fig. 8 includes an ear 37 which when assembled is adhesively secured to an opposite corner 38 on the blank which is connected to end flap 30 by a perforated fold line 39 to thereby continuously connect the respective end and side flaps 30, 26. This provides a top which is leakproof around the entire periphery thereof due to the gusseted construction throughout.

The foregoing container structures are economical of material, well adapted for machine manufacture, and when set up are extremely rigid and leakproof. The automatic set-up and locking

elements are simple in nature and unfailing in operation, while the tuck-in seal is likewise simple and highly satisfactory in operation.

I have illustrated and described my improvements in embodiments which are very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

1. A box or carton having opposed side and end walls secured to one another and constituting a flat tubular open-ended form in the initial, inoperative, knockdown condition of the box, side flaps integrally connected to said side walls and bent inwardly of said form to lie against the side walls in said knockdown condition, said flaps having locking means offset laterally from one another, and end flaps bendably connected to the end walls and lying thereagainst interiorly of said form, said side flaps having portions bendably connected thereto by score lines adapting the portions to be reversely bent and initially disposed against the side flaps, said portions being lapped over said end flaps along the entire adjacent edge of the latter and being adhesively secured to the end flaps by the aforesaid bendable connection to the side flat portion, whereby said portions and end flaps in operative erected condition constitute a substantially integral, leakproof bellows corner for the bottom of the box, said side and end flaps being swung to erected position normal to the walls upon relative lateral shifting of the walls, with the end flaps disposed in-

ternally of said side walls and side flaps, said locking means engaging operatively at the termination thereof to lock the flaps in operative erected position and thereafter resist return movement of the flaps and walls to original position, at least one of said end flaps being of width sufficient to laterally engage the side walls in erected position along a substantial portion of the length of the opposite sides thereof to further resist said return movement.

2. A box or carton having side and end walls secured together to provide an initial tubular form, a pair of side flaps connected to said side walls and bent inwardly of the form to lie against the side walls, and a pair of end flaps connected to the end walls and disposed interiorly of the form, said side flaps having portions bendably connected thereto by score lines adapting the portions to be reversely bent and disposed against the side flaps, said portions being lapped over said end flaps along the entire adjacent edge of the latter and being adhesively secured to the end flaps whereby said portions and end flaps constitute an integral leakproof bellows corner for the bottom of the box, said side and end flaps being swung to erected position normal to the walls upon relative lateral shifting of the walls, one of said side flaps having a locking slit therein and the other thereof having a locking projection engageable in said slit in operative erected position of the box to thereafter resist return of the flaps and walls to original position, at least one of said end flaps having parallel opposite sides and being of sufficient width whereby said opposite sides laterally engage the adjacent side walls to further resist return of the flaps and walls to original position.

FRED J. ULLRICH.
